United States Patent Office.

CHARLES W. TREMAIN, OF CHICAGO, ILLINOIS.

Letters Patent No. 84,820, dated November 24, 1868.

IMPROVEMENT IN BOILER-TUBE SCRAPER.

The Schedule referred to in these Letters Patent and making part of the same.

To whom it may concern:

Be it known that I, CHARLES W. TREMAIN, of Chicago, in the county of Cook, and State of Illinois, have invented a new and useful Improvement in Boiler-Tube Scrapers; and I do declare that the following is a true and accurate description thereof, reference being had to the accompanying drawings, and to the letters of reference marked thereon, and being a part of this specification.

Figure 1 is a back-end view.

Figure 2 is a top view.

Figure 3 is a front-end view.

Figure 4 is a longitudinal view with parts removed.

The object of this invention is the construction and arrangement of an apparatus for cleaning boiler-flues, and is constructed in the following manner:

A are semicircular disks, provided with guides, F, and are hinged at H by pivot L, to which is hinged and secured, inside, rod I, which passes through the chamber in disk A", and is allowed to oscillate freely. The front disk is provided with the chamber D, in which is inserted spiral spring C, which serves to extend the periphery of the disk, that it may be sure to come in contact with the walls of the flues, in its passage through them.

The projections F serve to guide and brace the disks. The projecting lips E are to cover the opening space between the disks, and prevent the entrance of any foreign matter that might get between the disks, and prevent the working of the same.

The operation of this invention is simple and well understood.

B represents the boiler-flue, into which is inserted the scraper, constructed as above described. The scraper should be passed through the tube, turned a quarter round, when, in the act of pulling it out, it comes in contact with all parts of the flue not already cleaned.

What I claim as my invention, and desire to secure by Letters Patent, is—

The boiler-tube scraper, consisting of the opening disks A' A", chamber D, spring C, guides F, and lips E, connected to rod I, arranged substantially as set forth.

CHARLES W. TREMAIN.
